UNITED STATES PATENT OFFICE.

WILLIAM P. KOOKOGEY, OF BROOKLYN, ASSIGNOR TO THE KOOKOGEY ELECTRIC COMPANY, OF NEW YORK, N. Y.

GALVANIC BATTERY.

SPECIFICATION forming part of Letters Patent No. 407,781, dated July 30, 1889.

Application filed August 27, 1888. Serial No. 283,902. (No model.)

To all whom it may concern:

Be it known that I, WILLIAM P. KOOKOGEY, of the city of Brooklyn, in the county of Kings and State of New York, have invented a new and useful Improvement in Galvanic Batteries, of which the following is a specification.

My invention relates to the method of connecting, both mechanically and electrically, the series of electrodes or elements of a single cell both to the cell and to each other; and it consists, in general, of suspending all the several elements of like kind separately from a plate or casting on top of the cell by means of hook-shaped tops resting in a continuous horizontal groove in the plate, which groove contains mercury. If both the positive and negative elements are so arranged, they of course have separate plates insulated from each other. Its object is simplicity and cheapness of manufacture, and also better electrical connection.

In the accompanying drawings, in which the same characters indicate analogous parts, Figure 1 is a top view of a plate or casting from which one series of elements—*e. g.*, carbon—is to be suspended. Fig. 2 is a top view of a plate or casting for the other series of elements—*e. g.*, zinc. Fig. 3 is a vertical section on the line *xx* of Figs. 1 and 2, showing the two plates superimposed. Fig. 4 is a vertical section of one of a series of elements on line *yy* of Fig. 2 when in position in a battery.

A is a plate or casting, preferably made of metal, having projections *a*, by which it rests upon the top of the cell B. In Fig. 1 the parts marked with perpendicular lines are meant for open spaces. Continuous grooves *c* are cut or cast in the plate A and are intended to hold a small quantity of mercury, the cell being carefully leveled when it is put up.

In Fig. 2, plate D has a similar construction, having continuous grooves *e* and projections *f*, by which it rests upon plate B, there being insulating material *d*, Fig. 3, between the two plates when in position. The different elements of the battery hang down separately from these grooves, each one having, Fig. 4, a hook-shaped top *i*, made of heavy wire or conducting material, the end of which enters

the mercury of the grooves. The positions of the respective elements in the battery are shown at *j* and *j'*. A projection from the casting A or an attachment to it is shown at *k*, 55 having in it a mercury-cup *k'*, and a groove by which the mercury is connected with the mercury of the other grooves upon that casting. A similar mercury-cup is shown at *m* upon the plate D. These take the place of 60 binding-posts for connecting with the other cells or with the line. I speak of them as “cups,” since they must be enlargements of the groove system in order to receive connections large enough to prevent resistance. 65

The form of the supporting-plates is not essential, nor is it essential to have a double set of grooves upon either plate. The main idea is that there shall be electrical connection between all the elements of like kind by 70 means of mercury in a groove upon the plate which supports the elements. The plate itself may even be made of insulating material; but it is preferably made of metal.

The advantage of this form of battery is 75 that it is cheaply made, the grooves being cast in; no screws or nuts or bolts are necessary to attach the elements to the cell; and the elements may be easily removed, either separately or together. The electrical connection 80 is also better than in an ordinary battery, for the connection is by means both of the mercury and the metal of the plates. It frequently happens that by the oxidation of metal, when that is the only conductor used 85 as in the common battery, the conductivity is decreased or destroyed. The invention is appropriate to either a single-liquid or a two-liquid battery. If desirable, the ordinary binding-posts may be attached to the plates 90 A and D at any point for connection with other cells or with the line. This manner of connecting a cell and its electrodes may be applied to cells of single elements as well as those containing a series, as it is a simple but 95 highly efficient connection; but it has especial advantage when applied to large cells containing a series of elements.

I claim as my invention—

1. In an electro-galvanic cell, the combination of an electrode provided with a hook-shaped top, with a support from which the

electrode hangs, such support having a groove or cavity to contain mercury, substantially as and for the purpose described.

2. In an electro-galvanic cell, the combination of a plate or casting which rests on the top of the receptacle, having openings through which all the elements of the battery of like kind are suspended, and having a continuous groove upon its upper surface to contain mercury, with a series of elements of like kind having hook-shaped tops to rest in the mercury-grooves, substantially as and for the purpose described.

3. An electro-galvanic cell consisting of a receptacle for the solution, two separate plates insulated from each other to rest on top of the receptacle, each of such plates having openings through which the elements of the battery may be suspended, and also having a

continuous groove upon its upper surface to contain mercury, and two series of positive and negative elements having hooked-shaped tops to rest in the mercury-grooves of the respective plates, substantially as and for the purpose described.

4. In an electro-galvanic cell having its elements suspended therein by hooks resting in mercury which is held on a supporting-plate, a cup for mercury formed as a part of or attached to such supporting-plate, substantially as and for the purpose described.

In witness whereof I have hereunto put my hand, this 24th day of August, 1888, in the presence of two witnesses.

WM. P. KOOKOGEY.
